UNITED STATES PATENT OFFICE.

BENJAMIN R. WILLIAMS, OF ENGLISH, ARKANSAS.

ELECTRIC-LIGHT-BULB SHIELD.

No. 905,483.

Specification of Letters Patent.

Patented Dec. 1, 1908.

Application filed March 18, 1908. Serial No. 421,843.

To all whom it may concern:

Be it known that I, BENJAMIN R. WILLIAMS, a citizen of the United States, residing at English, in the county of Jefferson 5 and State of Arkansas, have invented certain new and useful Improvements in Electric-Light-Bulb Shields, of which the following is a specification.

My invention has relation to electric light 10 bulb shields, and consists in a shield of two or more parts, adapted to be removably secured to the electric light bulb socket, and to be shifted from side to side on the same.

The bulb may be round, oval, sphere- 15 shaped, or of any other appropriate shape, in which case the shields will conform to the shape of the bulb.

The shields are intended to shade the light, and they may be of any color, and in 20 use, both shields may be of the same color, or may be of different colors.

The invention is so constructed that only 25 one shield may be used at a time, or both may be used at the same time, and the invention is so constructed that one or both of the shields may be removed, or one may be slipped around so as to cover the other one, and thus have a double shade on one 30 side of the bulb, leaving the other side of the bulb open to throw its full light; thus any part of the room may be partly darkened, while the other part may be brilliantly lighted up.

In the accompanying drawings, Figure 1, 35 is an elevation, partly in perspective, partly in section and partly represented by dotted lines, of a socket and an electric light bulb, with my shields attached thereto. Fig. 2, is an elevation of the socket in perspective, 40 and the other parts of my invention in section. Fig. 3, is a cross-sectional view of Fig. 1, on the line $\alpha\alpha$, showing an additional half band 9. Fig. 4, shows a cross-sectional view, in modified form, of Fig. 2, 45 on the line $\beta\beta$, showing the necks of the shields in cross-section, but the neck of the socket and lining thereof are not in cross-section, and the half band 9, is not shown in this view. Fig. 5, is a cross-sectional view 50 of Fig. 1, on the same line $\alpha\alpha$, showing the neck of the socket and the shields, all in cross-section, the binding-band being left off.

Referring more particularly to the drawings, the numeral 1, represents the socket; 55 2, the key, through the medium of which the

electric circuit is turned on or off; 3, represents the neck of the socket; 4, the lining of the neck; 5, the bulb, which is screwed into the neck of the socket; 6 and 6¹, represent the shields; 6² 6³, the necks of the shields; 7, an annular ridge, surrounding the neck of the socket near its lower end; 8, represents annular grooves in the inner faces of the necks of said shields, which fit over said 60 annular ridge; 9, represents a half band, which encircles the neck of the socket and extends half way around the same; 10, the binding-band; 11, the perforated ears and 65 12 a threaded binding screw, which passes through the perforations of said ears. 70

It will be observed that in Fig. 1, I represent the socket 1, key 2, neck to the socket 3, lining to the socket 4, bulb 5, shields 6 and 6¹, the binding-band 10, ears to binding-band, 75 11, and binding-screw 12, but in Fig. 3, I do not show the lining 4, to the neck, but I show an additional half band 9.

In Fig. 5, I show the neck 3, lining 4 and necks 6² and 6³ of the shields 6 and 6¹. 80

In Fig. 4, the necks 6² and 6³ of the shields are in section, but the neck of the socket and lining to the neck are not in section.

The operation of my invention is as follows:—The shields 6 and 6¹ are so formed at 85 their edges that they slightly overlap each other, so that there may be no crack left between the edges of the same for the white light to pass through. When I desire the whole room to be darkened, or the light to 90 be modified, I put the shields 6 and 6¹ in their proper place, and hold them there by means of the binding-band 10 and screw 12. If I desire only part of the room darkened I slip the shield 6¹ around over the shield 6, 95 and therefore have on that side of the bulb a double shield, while the other side is open. In this case the shield 6¹ is a little larger than the shield 6 and conforms to the curve of the half band 9, which holds the shield 6¹ 100 out a little beyond the immediate track of the shield 6.

In my modified form I do not use the extra half band 9, and when I wish to darken only part of the room, I loosen the binding- 105 band, and entirely remove one of the shields.

Although I have specifically described the combination, construction and arrangement of the several parts of my invention I do not confine myself particularly to such specific 110 combination, construction and arrangement, as I may claim the right to make such modi-

cation and changes therein as may clearly fall within the scope of my invention, and which may be resorted to without departing from the spirit, or sacrificing any of my patentable rights therein.

Having described my invention, what I claim as new and desire to secure by Letters Patent, is:—

1. In combination with an electric bulb socket 1, an annular ridge 7, around the neck 3, of said socket near its lower end; a pair of shields 6 and 6¹, adapted to surround the bulb 5, said shields adapted to overlap each other at their edges, each being provided in their necks with internal annular grooves 8, adapted to fit over said ridge 7; a half band 9, fitting half way around said neck of said socket; a binding-band 10, provided with perforated ears 11, fitting around the necks of said shields, and adapted to hold said shields in place, and a thread-

ed binding-screw 12, passing through the perforated ears of said band, and adapted to hold same in place, substantially as shown and described and for the purposes set forth. 25

2. In combination with an electric bulb socket, provided with a downwardly extending neck, a pair of shields adapted to inclose the bulb, each provided with a neck adapted to fit the neck of said socket, one of said shields being slightly larger than the other and adapted to slip over the same, and a binding-band adapted to encircle the necks of said shields, and hold the same in place, substantially as shown and described and for 30 the purposes set forth.

In testimony whereof I affix my signature, in presence of two witnesses.

BENJAMIN R. WILLIAMS.
